UNITED STATES PATENT OFFICE.

AUGUSTUS T. GILLENDER, OF NEW YORK, N. Y.

WALL MATCH-SAFE.

SPECIFICATION forming part of Letters Patent No. 274,310, dated March 20, 1883.

Application filed December 19, 1882. (No model.)

To all whom it may concern:

Be it known that I, AUGUSTUS T. GILLENDER, of the city, county, and State of New York, have invented a new and useful Improvement in Wall Match-Safes, of which the following is a full, clear, and exact description.

Reference is to be had to the accompanying drawings, forming part of this specification, in which similar letters of reference indicate corresponding parts in both the figures.

Figure 1 is a perspective view of my improvement. Fig. 2 is a sectional side elevation of the same.

The object of this invention is to provide wall match-safes constructed in such a manner as to receive a box of matches and expose the prepared side of the box for the matches to be ignited upon, while at the same time affording a receptacle for the partly-consumed matches.

20 A represents the back plate of the safe, which is provided with holes A' to receive the nails or screws by which the safe is secured to the wall.

Upon the forward side of the upper part of the plate A is formed a receptacle, B, open at the top, and of such a shape and size as to receive a box of matches. I prefer to make the receptacle B sufficiently large to allow the outer case, C, of the box to be placed within 30 it, and the inner case, C', containing the matches, to be placed upon the said outer case, as illustrated in Fig. 2.

In the forward side of the receptacle B is formed an aperture, B', of such a shape and size as to allow a match to be inserted through it and drawn along the prepared surface of the outer case, C, of the match-box, and thus ignited.

40 In the bottom of the receptacle B is formed an aperture, B², through which a finger can be inserted to raise the match-box, so that it can be removed when empty and another box inserted.

Upon the forward side of the lower part of

the plate A is formed a receptacle, D, of such 45 a size as to receive a box, E, for the matches to be placed in after being used.

In the bottom of the receptacle D is formed an aperture, D', through which a finger can be inserted to raise the box E, so that it can be 50 removed and emptied when required.

The box E is made of metal, so that it will not be liable to be set on fire should a match be placed in it without being extinguished.

The safe can be made of metal, wood, or 55 other suitable material.

With this construction the unused matches will always be in the upper receptacle and the used or partly-burned matches in the lower receptacle, so that the user will not be liable to 60 take a partly-burned match instead of an unused one. Another advantage of this construction is that with each new box of matches there will be a fresh surface to ignite the matches upon, so that the matches can always be ignited readily.

Having thus described my invention, what I claim as new, and desire to secure by Letters Patent, is—

1. A wall match-safe made, substantially as 70 herein shown and described, with a suspension-plate, A, having upon its upper part a receptacle, B, provided with a front opening, B', and a bottom opening, B², and upon its lower part a receptacle, D, provided with a bottom 75 opening, D', as set forth.

2. A match-safe consisting of the plate A and two top-open and bottom-closed receptacles, B D, the latter placed one above the other, and each provided with a hole in the 80 bottom, whereby the contents of each receptacle may be raised, so as to be taken hold of with the fingers, as described.

AUG. T. GILLENDER.
